UNITED STATES PATENT OFFICE.

ARCHIBALD FINDLAY MCKENZIE, OF WHYTEWOLD, MANITOBA, CANADA.

ATTACHMENT TO SAW-VISES.

1,308,248.

Specification of Letters Patent.

Patented July 1, 1919.

Application filed May 17, 1917. Serial No. 169,290.

To all whom it may concern:

Be it known that I, ARCHIBALD FINDLAY MCKENZIE, a subject of the King of Great Britain, and a resident of the village of 5 Whytewold, in the Province of Manitoba, Canada, have invented certain new and useful Improvements in Attachments to Saw-Vises, of which the following is the specification.

10 The invention relates to improvements in attachments to vises, particularly saw vises, and the object of the invention is to provide a magnifying glass attachment to a vise which can be readily adjusted for use in the 15 operation of sharpening a saw blade to allow one to do better work owing to the magnifying of the teeth due to the glass.

With the above object in view the invention consists essentially in a carrying bar 20 attached to the vise, a magnifying glass and an adjustable mounting for the glass in respect to the bar, the parts being arranged and constructed as hereinafter more particularly described and later pointed out in 25 the appended claim, reference being had to the accompanying drawing in which:—

Figure 1 represents a plan view of the attachment as applied to the vise.

Fig. 2 represents a vertical sectional view 30 through the vise showing the attachment in side elevation.

Fig. 3 represents an end view of the sleeve supporting the glass.

In the drawing like characters of reference indicate corresponding parts in the several figures.

The present invention is described as associated with a specially constructed saw vise which forms the subject-matter of Patent 40 No. 1,266,135, issued May 14, 1918, to applicant. On this account I have not considered it necessary to herein enter into a detailed explanation of the vise itself.

Referring now to the drawing:—

45 1 represents a work bench to the upper corner of which I have secured my vise indicated generally by the reference figure 2, which vise presents a pair of similar suitably spaced adjustable brackets 3 and 4 which carry the movable jaw 5 of the vise, the jaw being constructed and positioned to clamp in against the strip 6 permanently attached to the side of the work bench and passing lengthwise thereof. The adjust-

ment is effected by manipulating the levers 55 7 and 8.

The inserted saw blade 9 is held permanently in position between the jaw 5 and the strip 6 when the levers are clamped.

In order to facilitate the work of sharpening a saw placed in the vise I have provided the vise with the attachment now described which forms the subject matter of this application.

Immediately to the outer side of the jaw 65 5 and carried by the ends of the brackets I locate a horizontal carrying bar 10 which is substantially rectangular in cross section and is parallel to the jaw.

On this bar I mount slidably an upstanding standard 11 which has the upper end thereof fitted with spaced upstanding lugs 12 and 13 and has the lower end thereof cut away at 14 and notched at 15, the notch receiving the bar. A retaining plate 16 is 75 placed in the notch and screwed to the standard and serves to retain the bar in sliding relation to the standard.

17 is an adjustable rod like arm pivotally fastened at 18 to the upper end of the 80 standard, the arm actually passing between the lugs and being fastened thereto by means of a bolt 19 which passes through both the lugs and the arm and is fitted with a winged nut 20, the arrangement being such that 85 when the nut is loosened the arm can be adjusted in the vertical plane and when the nut is tightened the lugs will be drawn in to jam against the arm and hold the arm in any adjusted position.

90 On the arm I mount adjustably a magnifying glass 21 of which 22 is the usual band or ring. The ring is supplied with an extending lug 23 which is received between the opposing ends 24 and 25 of a split sleeve 95 26 slidably mounted on the arm and connected to the lug 23 by means of a bolt 27 passed through the lugs and ring and provided with a winged nut 28. The arrangement at this point is such that when the nut 100 is tightened it not only jams the split sleeve on the arm but also jams the ends of the sleeve against the lugs. Accordingly a double adjustment can be effected at this point. The sleeve can be moved in or out on the 105 arm and the glass can be swung in respect to the sleeve.

When the appliance is in use one simply

adjusts it to accommodate his vision when sharpening his saw and as the sharpening operation continues he shifts the attachment endwise on the bar 10 without requiring to 5 make any further adjustment.

Obviously the operation of sharpening a saw is greatly facilitated by this appliance and is much easier on the eyes of the one doing the work.

10 What I claim as my invention is:—

In an attachment to saw vises, the combination with adjustable end brackets and a clamping jaw connecting the brackets, of a horizontal bar secured to the brackets and 15 parallel with and to the outer side of the

jaw, an upstanding standard mounted on the bar and slideable endwise of the bar, a rod pivotally secured to the upper end of the standard and adjustable in the vertical plane and a magnifying glass suspended from the 20 rod and located at right angles thereto and adjustable outwardly and inwardly on the rod.

Signed at Whytewold, this first day of May, 1917.

ARCHIBALD FINDLAY MCKENZIE.
